UNITED STATES PATENT OFFICE.

CHARLES PETTIT SUGG, OF SPOTTSVILLE, KENTUCKY.

SAFETY DEVICE FOR ELEVATORS.

1,219,050.

Specification of Letters Patent. Patented Mar. 13, 1917.

Application filed November 29, 1916. Serial No. 134,142.

To all whom it may concern:

Be it known that I, CHARLES PETTIT SUGG, a citizen of the United States, residing at Spottsville, in the county of Henderson and State of Kentucky, have invented certain new and useful Improvements in Safety Devices for Elevators, and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in safety devices for elevators and comprises a simple and efficient device of this nature so arranged that, in the event of the hoisting cable for raising the elevator becoming broken, automatic means is actuated to check the descent of the same.

The invention comprises various details of construction, combinations and arrangements of parts which will be hereinafter fully described, shown in the accompanying drawings and then specifically defined in the appended claims.

Illustrate my invention in the accompanying drawings which, with the letters of reference marked thereon, form a part of this specification and in which:—

Figure 1 is a front elevation of an elevator having my safety apparatus applied thereto.

Fig. 2 is a central vertical sectional view through the same.

Fig. 3 is a side elevation.

Reference now being had to the details of the drawings by letter, A designates the guides for the car, which are provided with elongated openings B in the walls thereof, the upper and lower marginal edges of said openings being inclined as shown in the sectional view of the drawings, opening being upon the inner face. The car is designated by letter D and has plates E projecting from the sides thereof, the opposite edges of which plates are flanged and adapted to guide the car as it is raised and lowered by said flanges engaging over the edges of said guides. Said plates are bent toward each other at point designated by letter F and one of the plates is bent horizontally at point designated by letter K and has a

horizontal portion K', the edge of which is fastened to the upper end of the opposite plate. Said horizontally disposed portion of the plate is apertured for the reception of the post N, which latter is pivoted to a block O having its opposite ends inclined as shown and which conform to and are parallel with the inclined portions of said plates described. The block O has recesses R formed in its upper edge and, S is a coiled spring seated in said slots and bearing against the lower edges thereof and surrounding said post, while the upper end of the spring bears against the under surface of said horizontally disposed portion of the plate. It is the purpose of said spring to normally hold the block O at its farthest lowest limit. A cable, designated by letter T, is fastened to the upper end of said post and said cable is adapted to wind about drums or pulleys, not shown, and forms a means for raising and lowering the elevator.

Pawls, designated by letter L, are pivotally mounted upon the pins I passing through the block O near the lower edge thereof and near the outer ends of the block. Said pawls are disposed at inclinations and are guided in the apertures Q formed in said plates and the free ends of said pawls are beveled as shown in the vertical sectional view in the drawings and are adapted, when the weight of the car is supported by the cable, to be held at their farthest upper limits and in which positions their beveled ends will be flush with the outer faces of the apertured plates through which said pawls extend.

When the weight of the elevator is supported by the cables, it will be noted that the spring is under tension and, in the event of the cable breaking, the spring will throw the block O to its lowest limit and the free ends of the pawls will be thrown out through the openings in said plates and, when they come in contact with the lower inclined marginal edges of the openings in the guides for the car, they will serve as stops to prevent the elevator falling. Said openings are disposed at various locations along the opposite side walls of the frame so that the elevator will be caught quickly without attaining any great momentum in the event of breakage of the cable.

An upward pull upon the cable will cause

the block O to be raised and the pawls which are pivoted thereto will be drawn upward so that their free ends will disengage the lower inclined ends of said openings, thus 5 permitting the elevator to be raised. It will be noticed that, when the weight of the elevator is constantly upon the cables, said pawls will be drawn back so that they will not in any way interfere with the elevator 10 frame.

What I claim to be new is:—

1. A safety device for elevators comprising a car guide having oppositely disposed openings, the upper and lower edges of 15 which are beveled, plates, the edges of which are flanged and adapted to engage said car guides, said plates being apertured, the upper portions of the plates being bent toward each other and fastened together, said plates 20 having a horizontally disposed portion which is apertured, a post movable through said aperture in the horizontal portion, a block to which said post is pivoted, said block having recesses in its upper edge, a 25 spring seated in said recesses and bearing against the horizontal portion of one of said plates, a cable secured to said post, pawls carried by the post and movable through

apertures in the plates and designed to engage the openings in said guide. 30

2. A safety device for elevators comprising a car guide having oppositely disposed openings, the upper and lower edges of which are beveled, plates, the edges of which are flanged and adapted to coöperate with 35 the car guide, said plates being apertured, the upper portions of the plates being bent toward each other and fastened together, said plates having a horizontally disposed portion which is apertured, a post movable 40 through said aperture in the horizontal portion, a block to which said post is pivoted, the ends of said block being inclined and the upper edge provided with recesses, a spring seated in said recesses and bearing against the horizontal portion of one of said plates, pawls pivoted to the ends of said block and movable through apertures in the plates, the free ends of the pawls being beveled. 45

In testimony whereof I hereunto affix my signature in presence of two witnesses.

CHARLES PETTIT SUGG.
